MANIFOLD REGISTER

Roy R. Smith, Jr., Kansas City, Mo.

Application September 4, 1943, Serial No. 501,234

5 Claims. (Cl. 282—18)

This invention relates to manifold registers, the principal object of the invention being to provide a convenient, economical and efficient register for manifolds.

Features of prime importance in the invention are arrangements by which the entire area of each of the respective manifold sections including carbons may be utilized for writing purposes by the operator; lines of section severance and manifold moving apertures interfere in no way with the writing surfaces of the manifold; the entire area of consecutive manifold sections is available for receiving impressions and the manifold sections are moved to impression receiving position in a very simple but expeditious manner.

Other objects of the invention are to provide a manifold advancing device adapted to cooperate with the manifold for aligning the individual manifold sections with a writing space of the register; to provide a pin type feeding device in a register, the spacing of the pins being the same as the length of the manifold form; to provide a register with a movable panel for covering the opening from which the manifolds issue; to provide a hinged panel having an opening defining a writing space; to provide a device at one boundary of the writing space to facilitate tearing of the individual forms; to provide for support of a carbon between the manifold sheets used in the register, said carbon being advanced transversely of the register; to provide a register having a neat and attractive appearance and exposing only the form on which writing is to be placed; and to provide improved elements and arrangements thereof in manifold registers of the character and for the purposes set forth.

In accomplishing these and other objects of the invention, I have provided improved details of structure, the preferred forms of which are illustrated in the accompanying drawings, wherein:

Fig. 1 is a perspective view of a register embodying my invention.

Fig. 2 is a transverse sectional view through the register on the line 2—2, Fig. 3, illustrating the feeding device and the guides for holding the forms thereon.

Fig. 3 is a longitudinal sectional view through the register on the line 3—3, Fig. 2.

Fig. 4 is a perspective view of a manifold adapted for use with the register.

Fig. 5 is a perspective view of the register with the upper portion thereof shown in raised position to illustrate the interior thereof.

Fig. 6 is a fragmentary perspective view of

the register showing the panel defining the writing space in raised position.

Fig. 7 is a transverse sectional view on the line 7—7, Fig. 1, particularly illustrating the relation of the carbon and manifold in the register.

Referring more in detail to the drawings:

10 1 designates a register including a housing consisting of a base 2 and a cover 3. The base 2 consists of a bottom 4, on which are upwardly extending sides 5 and front and back walls 6 and 7, the wall 7 preferably being higher than the wall 6 and the wall 5 sloping toward the rear to provide a flat peripheral edge 8 adapted to be matedly engaged by edges 9 of side walls 10 and 11 and front and rear walls 11 and 12 respectively of the cover 3, said walls of the cover 3 being connected by a panel 13 forming the top of the register housing.

15 The cover member is preferably hinged to the base member, the rear walls 7 and 12 preferably being connected by hinges 14 whereby the cover member may be raised from the base member to provide access to the interior of the register, the extent of the cover opening being limited by means

20 of a chain or other suitable connection 15. Centrally mounted in the register housing on the bottom 4 thereof are spaced upwardly extending members 16 and 17, preferably having laterally turned flanges 18 and 19 to form a hopper 20 for a packet or the like of manifold forms 21. The members 16 and 17 preferably have outwardly extending flanges 21 and 22 adapted to engage the base 4 for securing the members thereto. The flange 18 preferably extends above the upper edge 23 of the member 16 to provide guides 24 for the sides of the manifold as it is being fed from a packet to the feeding device, as later described.

25 Cooperating with the upper edge 23 of the member 16 is a downwardly extending rib 25 on the cover 3 spaced slightly to the rear of the member 16, said rib 25 being notched, as at 26, to provide side edges 27 adapted to cooperate with the guides 24 on the member 16. The edge 28 of the notched portion of the rib 25 cooperates with the surface 23 of the member 16 to guide the manifold into engagement with a feeding device such as a cylinder 29 preferably having outwardly

30 extending trunnions 30 adapted to rest in bearing slots 31 of bosses 32 on the sides 5 of the base member 2. The cylinder 29 is adapted to be rotated on the trunnions 30, preferably by means of a hand-wheel mounted on an end of the cylinder 29 and of larger diameter than the cylinder whereby the edge of the wheel 33 extends through a slot 34 in the cover member 3. The slot 34 and

35

40

45

50

55

the exposed portion of the wheel are located at the back and right side of the register in convenient position for the operator to actuate same by drawing the palm of his hand over the roller 33.

The cylinder 29 is preferably provided with pins 35 projecting from the surface of said cylinder. The pins are preferably arranged in spaced relation corresponding to the distance between transverse lines of severance defining the sections of the manifold, and adapted to engage apertures 36 of the manifold to feed said manifold through the register.

The preferred form of manifold is arranged in a packet, as shown in Fig. 4, and consists of a plurality of individual forms 37 preferably separated by lines of perforations 38 which are arranged to form the fold line 39 by which the manifold is formed in the shape of the packet. With this arrangement, the apertures 36 occur on the 20 fold line and line of perforations. There is, thus, no aperture in the writing space of the individual form. It will also be noted that the entire area of each manifold section is available for receiving impressions. In order for the pins 35 to engage the apertures 36 in the manifold to properly feed same through the register, the cylinder 29 preferably has a circumference that is twice the length of the manifold. In that way the pins 35 are diametrically spaced in such a manner that one-half of a revolution of the cylinder 29 moves the manifold a sufficient distance to expose the next form and align it in the writing space as later described.

The surfaces 23 and 28 of the member 16 and rib 25 respectively guide the manifold into engagement with the cylinder 29 and the pins engage in the apertures 36. In order to assure close engagement between the manifold and the cylinder 29, spaced guide members 40 and 41 are arranged in the base and cover members respectively in alignment with the respective pins 35. The guides 40 and 41 are provided with grooves 42 and 43 of suitable size to provide clearance for the pins 35, yet permit the ribs 44 forming the sides of the groove to closely engage the cylinder 29 to hold the manifold 37 in close engagement therewith. The guides 41 terminate slightly forwardly of a vertical line projected through the center of the cylinder 29 where a slot 45 is provided in the cover to permit passage of the manifold to the upper surface of said cover. The upper surface 13 of the cover is recessed, as at 46, whereby the forms of the manifold lie below the surface 47 of the cover. The rear edge of the recessed portion of the cover is tapered downwardly, as at 48, and provided with notches in alignment with the pins 35 of the cylinder 29 to aid in stripping the forms of the manifold from the feeding device.

The recessed portion of the cover is provided with shoulders 50 spaced above the surface 46 a distance slightly greater than the thickness of the manifold sheet and below the surface 47 sufficiently to receive a panel 51 adapted to cover the slot 45 and align with the surface 47 to present a smooth surface at the top of the register. The panel 51 is preferably of U shape, whereby the legs 52 and 53 are of substantially the same length as the forms of the manifold and the extremities of the legs are provided with trunnions 54 adapted to seat in apertures 55 in the cover to hingedly mount the panel 51 thereon, said legs 52 and 53 being connected at the outer extremities thereof by a rod 56 to form an en-

closed opening of substantially the same size as the forms of the manifold, whereby the panel 51, when in lowered position on the cover 3, provides a space permitting writing over the entire surface of the individual form. When said form is advanced to align a new form in the opening, the perforated lines 38 are arranged slightly forward of the rod 56 whereby the written form may be lifted and drawn against the rod 56 to facilitate tearing of the form from the manifold. Spaced slightly forwardly of the rod 56 is a slot 57 in the cover 3 to permit insertion of the carbon copies of the written form into a storage chamber 58 in the interior of the register, the chamber 58 being separated from the remainder of the register by means of ribs 59 and 60 on the base and cover members respectively.

In order to facilitate raising of the panel 51, the leg 53 is provided with a lateral projection 61 and the cover is provided with a recess 62 whereby the projection 61 may be grasped by the fingers to lift the rear end of same and hinge the panel upwardly on the trunnions 54 to permit access to the slot 45 and facilitate feeding of a new manifold through the register.

If desired, pins 63 may be placed on the upper edge of the wall 6 adapted to engage in recesses in the edge 9 of the wall 11 to help hold the forward end of the respective portions of the register housing in alignment, the wall 6 being provided with a recessed portion 64 to facilitate grasping of the wall 12 to raise the cover from the base member 2.

In order to avoid the excessive use of carbon and/or the expensive operation of folding a carbon sheet in the manifold, I prefer to provide a separate carbon for the register, said carbon preferably being formed in a roll 65 mounted on brackets 66. The carbon is of a suitable width to conform to the length of the individual forms of the manifold, said carbon being fed through a slot 67 in the recess portion 46 of the cover 3 and extended transversely between the manifold forms. With this arrangement the carbon may be used until the second sheet becomes too dim for legibility. Then, by lifting the panel 51, the carbon may be grasped and drawn across the register and the used portion thereof may be torn from the roll, leaving a fresh carbon between the manifold sheets.

The operation of a register constructed as described is as follows:

The cover 3 is grasped at the recess 64 and the forward end thereof raised upwardly to hinge the cover member on the hinges 14 to expose the interior of the register. A manifold 37 formed in the shape of a packet, as shown in Fig. 4, is placed in the hopper 20 between the members 16 and 17. The upper form is drawn over the upper surface 23 of the member 16 and inserted between the cylindrical member 29 and the guide 40. The cylindrical member 29 is rotated as the form is inserted until a series of pins 35 engage in a series of the apertures 36 in the line of perforations 38 at the extremities of the individual forms. Continued rotation of the cylindrical member 29 moves the end of the manifold to the upper side of the cylindrical member at which point it may be grasped and inserted through the slot 45. The panel 51 may be hinged upwardly on the trunnions 54 to expose the slot 45, whereby the edge of the manifold may be grasped by the fingers and held while the cover 3 is moved to closed position. The wheel 33 may then be rotated by engagement of the palm of the hand thereon to advance the manifold over the top of the recessed portion of

the cover. The end of the manifold is then placed under the bar 56 and the panel 51 hinged to closed position whereby the entire area of a manifold section is exposed in the writing space therefor.

If a carbon of the form is desired, the carbon is drawn through the slot 67 and the upper sheet of the manifold is raised to allow extension of the carbon sheet thereunder prior to the closing of the panel 51. Proper information may then be written on the form exposed in the writing space, but when said writing is completed, engagement of the palm on the wheel 38 advances the manifold through the register until the next line of perforations is arranged slightly forwardly of the bar 56. It will be noted that the succeeding manifold section is immediately available and that its entire surface may be written upon. The ends of the first manifold may then be grasped to tear the individual forms therefrom. The carbon copy of the written form may then be inserted in the slot 51 for suitable storage in the manifold housing. When the portion of the carbon material arranged under the path of the manifold becomes used to the extent that it is not properly legible, the panel 51 may be raised and the upper sheet of the manifold lifted to expose said carbon sheet, which then may be drawn across the register until a new carbon is exposed under the manifold sheet and the end of the carbon torn off. The closing of the panel 51 then makes the register ready for additional use.

When a packet of manifolds is exhausted, the same procedure is repeated to fill the register again and make it ready for use, and the copies of the written forms in the storage in the register may be removed for inspection at any time.

With this arrangement, there is nothing to wear and it is extremely simple to load and manipulate the register.

It is apparent, therefore, that I have provided a convenient, economical and efficient manifold register that is admirably suited for the purpose for which it was designed.

What I claim and desire to secure by Letters Patent is:

1. A register for sectional manifold strips including a housing having upper and lower panel portions spaced apart to provide a passageway therebetween for movement of a sectional manifold strip, said upper panel portion having a window opening extending transversely of the passageway with opposite transverse edges spaced apart to correspond with the upper and lower edges of a section of said manifold strip and the lower panel portion forming a writing support for the leading section of said strip when the upper and lower edges of the section substantially register with the transverse edges of the opening, means in the housing for storing the sectional manifold strip, a feed roller extending transversely of the housing intermediate the storage means and said passageway, pins spaced apart on the periphery of the roller at a distance corresponding to the spacing between the transverse edges of the opening whereby said pins engage the upper and lower edges of one of the sections when the upper and lower edges of the leading section of said strip is in registry with the transverse edges of the opening, means for rotating the feed roller to push said leading section through said passageway and out of writing position and the succeeding section into writing position with the upper and lower edges registering with said transverse edges of the opening while the upper and lower edges of another section of said

strip is engaged by said pins, said writing support having a size to support a carbon sheet at least the size of the manifold sections whereby an exact copy can be made of a manifold section when written upon anywhere on the area of a manifold section.

2. A register for sectional manifold strips including a housing provided with a top having a depressed panel portion, a panel covering said depressed panel portion and spaced therefrom to provide a passageway therebetween in connection with the interior of the housing at one end and opening exteriorly of the housing at the other for movement of a sectional manifold strip therethrough, said panel having an opening extending transversely of the passageway with opposite edges spaced apart to correspond with the upper, lower, and side edges of a section of said manifold strip, said lower panel portion forming a writing support for the leading section of said strip when the upper and lower edges of said section substantially register with the transverse edges of the opening, means in the housing for storing the sectional manifold strip, a feed roller extending transversely of the housing intermediate the storage means and said passageway, pins on the feed roller spaced apart on the periphery of the roller at a distance corresponding to the spacing between the transverse edges of the opening whereby said pins engage the upper and lower edges of a section when the leading section of said strip is in registry with the transverse edges of the opening, and means for rotating the feed roller to push said leading section out of writing position and the succeeding section into writing position with the upper and lower edges registering with said transverse edges of the opening while the upper and lower edges of another section of said strip is engaged by said pins, said writing support having a size to support a carbon sheet at least the size of the manifold sections whereby an exact copy can be made of a manifold section when written upon anywhere on the area of a manifold section.

3. A register for sectional manifold strips including a housing having upper and lower sections, means connecting the sections for hinging the upper housing section on the lower housing section, said upper section of the housing having panel portions spaced apart to provide a passageway therebetween for movement of a sectional manifold strip, said upper panel portion having a window opening extending transversely of the passageway with opposite transverse edges spaced apart to correspond with upper and lower edges of a section of said manifold strip and the lower panel portion forming a writing support for the leading section of said strip when the upper and lower edges substantially register with the transverse edges of the window opening, means in the housing for storing the sectional manifold strip, a feed roller extending transversely at the hinged connection of the housing sections and intermediate the storage means and said passageway, pins spaced apart on the periphery of the roller at a distance corresponding to the spacing between the transverse edges of the opening whereby said pins engage the upper and lower edges of a succeeding strip section when the leading section of said strip is substantially in registry with the transverse edges of the opening, and means for rotating the feed roller to push said leading strip section through said passageway and out of writing position and the succeeding strip section into writing position with the upper and lower

edges registering with said transverse edges of the opening while the upper and lower edges of another section of said strip are engaged by said pins.

4. A register for sectional manifold strips including a housing having upper and lower panel portions spaced apart to provide a passageway therebetween for movement of a sectional manifold strip, said upper panel portion having a window opening extending transversely of the passageway with opposite transverse edges spaced apart to correspond with the upper and lower edges of a section of said manifold strip and the lower panel portion forming a writing support for the leading section of said strip when the upper and lower edges substantially register with the transverse edges of the opening, means in the housing for storing the sectional manifold strip, a feed roller extending transversely of the housing intermediate the storage means and said passageway, pins on the feed roller spaced apart on the periphery of the roller a distance corresponding to the spacing between the transverse edges of the opening whereby said pins engage the upper and lower edges of a section when the leading section of said strip is in registry with the transverse edges of the opening, and means for rotating the feed roller to move said leading section out of writing position and the succeeding section into writing position with the upper and lower edges registering with said transverse edges of the opening while the upper and lower edges of another section of said strip is engaged by said pins, one edge of said opening forming severance means for tearing off the leading section advanced across the opening.

5. A register for sectional manifold strips including a housing having upper and lower panel portions spaced apart to provide a passageway therebetween for movement of registered sectional manifold strips, said upper panel portion having an opening extending transversely of the passageway with opposite transverse edges spaced apart to correspond with the upper and lower edges of registered sections of said manifold strips and the lower panel portion forming a writing support for the leading sections of said strip when the upper and lower edges substantially register with the transverse edges of the opening, means in the housing for storing the sectional manifold strips in registry, a feed roller extending transversely of the housing intermediate the storage means and said passageway, pins on the feed roller spaced apart on the periphery of the roller a distance corresponding to the spacing between the transverse edges of the opening whereby said pins engage the upper and lower edges of the registered sections of the strips when the leading sections of the strips are in registry with the transverse edges of the opening, means for rotating the feed roller to move said leading section out of writing position and the succeeding registered sections into writing position with the upper and lower edges registering with said transverse edges of the opening while the upper and lower edges of another registered section of said strip is engaged by said pins, and means co-extensive with a side of the writing support for supporting a carbon sheet between said sections at the place of the window opening.

ROY R. SMITH, JR.
